CLAIM

The ornamental design for a motorcycle child safety belt, as shown and described.

DESCRIPTION

FIG. 1 is a perspective view of a motorcycle child safety belt showing my new design;

FIG. 2 is a front elevational view thereof;

FIG. 3 is a rear elevational view thereof;

FIG. 4 is an end elevational view thereof;

FIG. 5 is an end elevational view thereof; and,

FIG. 6 is a top plan view thereof, the bottom view being a mirror image of the top view shown in FIG. 6.

FIG. 1.

FIG. 2.

FIG. 6.

FIG. 3.

FIG. 5.

FIG. 4.
